UNITED STATES PATENT OFFICE.

MICHAEL F. O'KEEFE, OF MIDDLETOWN, CONNECTICUT.

VALVE-SEAT FORMER.

1,087,457.

Specification of Letters Patent. Patented Feb. 17, 1914.

Application filed April 23, 1912. Serial No. 692,599.

To all whom it may concern:

Be it known that I, MICHAEL F. O'KEEFE, a citizen of the United States, and a resident of Middletown, in the county of Middlesex and State of Connecticut, have invented a new and Improved Valve-Seat Former, of which the following is a specification.

My invention relates to the class of devices used for renewing the valve seats in faucets and like devices for controlling the flow of liquid, and an object of my invention, among others, is to provide a device of this class in which the valve seats around 15 openings of varying size may be accurately cut and finished.

One form of device embodying my invention and in the construction and use of which the object above set out, as well as 20 others, may be attained, is illustrated in the accompanying drawings, in which—

Figure 1 is a view in central longitudinal section through a device embodying my invention shown as attached to a faucet, the latter being broken away to illustrate the operation of the device. Fig. 2 is a side view of my improved former. Fig. 3 is an end view of the same with the handle removed.

30 In the accompanying drawings the numeral 6 denotes a faucet of ordinary construction having the usual diaphragm 7 with an opening 8 and a valve seat 9 around said opening.

35 The numeral 10 denotes the base of my improved former having an opening 11, preferably tapered from its outer to its inner end and provided with a screw thread 12 arranged to fit the screw threaded end 13 of 40 the faucet, the latter being provided for the reception of the cap common to these structures. A feeding sleeve 14 fits a screw threaded opening 15 through the base and is provided with a flange 16 that may be milled 45 to provide for turning as by the thumb and finger.

A spindle 17 is located within the sleeve 14 and a collar 18 removably secured to the spindle prevents it from movement in one 50 direction in the sleeve 14 and a shoulder formed by the enlarged head 19 prevents movement of the spindle in the opposite direction within the sleeve, so that the head 19 with its forming end 20 is carried and is 55 located by the sleeve. The upper end of

the spindle may be formed for the reception of any proper means for turning it, a handle 22 removably fitted to the spindle being shown herein for this purpose, the handle having a socket engaging the noncircularly 60 shaped end of the spindle. The forming end 20 of the head may be of a shape to provide such form of valve seat as may be desired, and a cutter guide 21 projects from this forming end into the opening 8 in the diaphragm 7. It is material that the lower end 65 of the spindle shall have a guide to nicely fit the opening in the diaphragm so that the former shall be centered to accurately cut the valve seat. The opening 8 varies in size 70 in different structures and in order that the guide may properly fit the opening to accurately center the former this guide is made a trifle larger than the openings of the devices for which it is intended and is provided with a cutting edge so that it will cut away the opening within the valve seat to a greater or lesser degree and then serve as a guide within this opening which it must necessarily closely fit. By constructing the 80 shoulders so that the spindle is carried and located by the feeding sleeve, when the valve seat has been cut to a sufficient degree the feed is stopped, and the cutter being held in this position a continued turning movement 85 of the spindle will cause the edge of the cutter to burnish, thus finishing the valve seat without cutting action.

While I have shown and described herein one form of device embodying my invention 90 this structure may be changed to a greater or lesser extent without departing from the spirit or intent of the invention as defined by the claim herein.

I claim—

A valve seat former including a base, having means for detachably securing it to a faucet or the like, a feeding sleeve located within the base and forming a bearing for a spindle, a former spindle carried by said 100 bearing, means for rigidly holding said spindle against longitudinal movement in either direction in said sleeve while permitting rotary movement of said spindle, and a cutter head secured to the spindle.

MICHAEL F. O'KEEFE.
